UNITED STATES PATENT OFFICE

WILBER L. ORME, OF CAMBRIDGE, OHIO

DESIGN FOR A GOBLET OR SIMILAR ARTICLE

Application filed December 17, 1930. Serial No. 38,020. Term of patent 3½ years.

To all whom it may concern:

Be it known that I, WILBER L. ORME, a citizen of the United States, residing at Cambridge, in the county of Guernsey and State of Ohio, have invented a new, original, and ornamental Design for Goblet or Similar Article, of which the following is a specification, reference being had to the accompanying drawing, forming part thereof.

Fig. 1 is a side elevation of a goblet showing my new design, and

Fig. 2 is a top plan view.

The dominant feature of the design resides in the ornamentation applied to the bowl of the goblet shown. The ornamentation is continued through the circumference of the bowl.

I claim:

The ornamental design for a goblet or similar article as shown and described.

WILBER L. ORME.
